Max Rothstein, Newton, Mass., assignor to The Dav-O-Niter Corp., Melrose, Mass., a corporation of Massachusetts

Application August 14, 1953, Serial No. 26,449

Term of patent 14 years

(Cl. D15—11)

To all whom it may concern:

Be it known that I, Max Rothstein, a citizen of the United States, residing at Newton, in the county of Middlesex, and State of Massachusetts, have invented a new, original, and ornamental Design for a Sofa Bed, of which the following is a specification, reference being had to the accompanying drawing, forming part thereof.

I claim:

The ornamental design for a sofa bed, as shown.

MAX ROTHSTEIN.
